UNITED STATES PATENT OFFICE.

JOHAN BAGGERUD, OF BROOKLYN, NEW YORK.

WATERPROOF TROUSERS-LEG PROTECTOR.

Application filed December 12, 1923. Serial No. 680,148.

To all whom it may concern:

Be it known that I, JOHAN BAGGERUD, citizen of Norway, residing at Brooklyn, in the county of Kings and State of New York, have invented certain new and useful Improvements in Waterproof Trousers-Leg Protectors, of which the following is a specification.

This invention pertains to the art of apparel, and has particular reference to an improved form of water proof protector for trousers legs.

The primary object of the invention is to provide an improved form of device adapted to be placed around the legs of trousers to protect them against becoming wet in inclement weather or to protect them against becoming soiled under any circumstance which the condition may arise.

Another object of the invention is to provide a waterproof trouser leg protector which shall be simple in construction and capable of being expeditiously and easily applied to or removed from the trousers legs.

Other objects will become apparent as the nature of the invention is better understood, and the same consists in the novel form, combination, and arrangement of parts hereinafter more fully described, shown in the accompanying drawing and claimed.

In the drawing, wherein like reference characters indicate corresponding parts throughout the several views:

Figure 1 is a side elevational view of a trousers legs protector constructed in accordance with the present invention partially applied to the leg portion of a pair of trousers.

Figure 2 is an enlarged transverse sectional view of the device shown in Figure 1 when completely applied, the plane of section being directly above the clips, and

Figure 3 is an enlarged perspective view of one of the clips.

Referring more in detail to the drawing, the present protector consists of a suitable sheet of water proof material indicated at 5, the length of which is that necessary to cover the desired portions of the trousers legs from the bottoms thereof upwardly, and the width of which is that necessary to

permit the same to be placed around the trousers legs so as to completely envelop the latter. This protector is made of some suitable waterproof fabric, and separable fasteners, such as the snap button members 6 and 7 are provided along the side vertical edges of the protector for detachably connecting said edges thereof when the device is disposed about the trousers legs. In order to effectively hold the protector in its proper position against downward movement on the trousers legs, a pair of opposed spring clips 8 are embedded in the upper edge portion of the sheet 5 in position to be clipped over the creased portions of the trousers legs at the front and back of the latter as shown by dotted lines in Figure 1. If desired, the sheet 5 may be formed of rubber or rubber composition with the clips 8 vulcanized therein and completely covered by the material thereof so that the clips will not injure the trousers legs when clipped onto the latter.

As shown in Figure 3, the clips 8 consist of strips of sheet metal centrally return bent and having their free ends directed outwardly or laterally away from each other as at 9, so that the clips may be readily slipped onto the trousers over the creased portions thereof.

In use, the sheet 5 is disposed about the trousers legs as shown in Figure 1, after which the snap fasteners or other separable fasteners composed of the members 6 and 7 are connected, the clips 8 having been previously snapped onto the trousers leg at the proper height. The device is thus effectively retained in place, and will protect the trousers legs against becoming wet or soiled. For removal, it is simply necessary to disconnect the vertical edges of the sheet 5 and withdraw the trousers legs from between the clips 8.

From the above description, it is believed that the construction and operation, as well as the advantages of the present invention will be readily understood and appreciated by those skilled in the art.

What I claim as new is:

A trouser leg protector formed from a piece of fabric adapted to encircle the lower

portion of the trouser leg, the ends of said protector being free and disposed in overlapping relation, separable fasteners carried by said overlapping ends for fastening the same together, and pairs of upper and lower front and rear clips carried by the protector and disposed on the interior there-

of to permit the arms of the clips to straddle the creases of the trouser legs for maintaining the protector in a taut state and in turn 10 keeping the trouser leg stretched.

In testimony whereof I affix my signature.

JOHAN BAGGERUD.
